CLAIM

The ornamental design for a computer host, as shown and described.

DESCRIPTION

FIG. 1 is a perspective view of a computer host showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view taken along line 9-9 in FIG. 7;

FIG. 10 is an enlarged view of the portion, labeled '10' of FIG. 9;

FIG. 11 is an enlarged view of the portion, labeled '11' of FIG. 1; and,

FIG. 12 is an enlarged view of the portion, labeled '12' of FIG. 9.

The even-dash broken lines illustrate portions of the computer host that form no part of the claimed design. The dot-dot-dash broken lines represent the extents of the detail views in FIGS. 1 and 9-12 and the direction of the section cut in FIG. 7. The oblique line shading shown in the drawings indicates a translucent surface.
